The ornamental design for an optical fiber connector, as shown and described.

DESCRIPTION

FIG. 1 is a top perspective view of an optical fiber connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a schematic perspective view thereof, shown in use environment.
The broken lines in the drawings illustrate portions of the optical fiber connector that form no part of the claimed design.**1 Claim, 7 Drawing Sheets**(56)
